WINDOW SASH OPERATING DEVICE

David E. Ross, La Fayette, Ind., assignor to
Rostone, Incorporated, La Fayette, Ind., a Cor-
poration of Indiana

Application August 15, 1932. Serial No. 623,947

4 Claims. (Cl. 268—132)

This invention relates to window sash operating devices, and while designed for use in connection with the window sash and frame shown in my co-pending application filed July 18, 1932, Serial No. 623,266 (Case #7958) is applicable to other types of window construction, and the like, wherein slideable sashes, or the like, are employed.

The invention provides simple geared sash operating devices whereby any sash may be raised or lowered at will by the operator and held in any adjusted position.

The accompanying drawings illustrate the present preferred embodiment of the invention and some modifications thereof, and I will describe the same with reference thereto, and summarize in the claims the novel feature of construction and novel combinations of parts for which protection is desired.

In said drawings:

20 Fig. 1 is a transverse sectional view through a window frame and sashes, such as described in the aforesaid application, equipped with my novel sash operating devices, the sash being broken to show the sash operating parts more clearly.

25 Fig. 2 is a side view of the sash operating devices shown in the right side of Fig. 1.

Fig. 3 is a view similar to Fig. 1 showing modifications of the sash raising devices.

Fig. 4 is a detail section on line 4—4, Fig. 1.

30 In Fig. 1 four sashes S, S', S² and S³ are shown slidably mounted in the window frame F which sashes and frame are shown as constructed in my aforesaid application. One of the side bars of each sash is provided with a rack indicated at 35 s, s', s² and s³ in Fig. 1. The racks extend the length of the sash and are engaged by operating gears as hereinafter described. As shown in Figs. 1 and 4 the rack s of sash S meshes with a gear 1b on a tubular shaft 1 which is rotatably mounted 40 in bracket 2 which may be formed on or attached to the outer side of the frame F, the shaft 1 being rotatable and also slideable in the bearing 2.

The outer end of the tubular shaft 1 may be provided with any suitable means for engagement 45 with an actuating wrench or key (not shown) and as shown in Fig. 1 a socket member 1c is attached to the outer end of the tubular shaft 1 and is adapted to be engaged by any suitable tool by which it can be pushed inward and also turned.

50 On the opposed faces of the bracket 2 and the gear 1b are interengaging lugs and slots. Preferably the lugs 2a are on the bracket 2 and the slots 1e are in the face of the gear 1b.

A spring 3 is arranged exterior to the tube be- 55 tween the socket member 1c and the bracket 2.

to move the shaft 1 outwardly so as to hold the lugs and slots in engagement as shown in Fig. 1 and when so engaged it is impossible to turn the shaft 1 and gear 1b. It is evident that if a crank or key is properly inserted in the cap member 1c and pushed inwardly the shaft 1 will be moved inwardly and move the gear 1b out of engagement with the lugs 2a while maintaining its engagement with the rack s and then the shaft 1 may be turned so as to rotate the gear 1b and raise or lower the sash S by reason of engagement of the gear teeth therewith.

After the sash has been adjusted to the desired position the inward pressure on the operating member is released and the latter withdrawn and 70 spring 3 moves the assembly (shaft 1 and gear 1b) outward interengaging the lugs and the slots 2a and 1e and firmly locking the sash S in ad- justed position.

To operate the sash S' a shaft 4 is extended 75 axially through the shaft 1 and may have an inner bearing in the bracket 2e attached to the frame F as shown. On this shaft 4 is mounted a gear 4b which meshes with the rack s' on sash S' and this gear 4b has radial slots 4e which 80 are adapted to mesh with radial lugs 2f on an adjacent bracket 2g on frame F. A spring 3a is interposed between the gear 4b and bracket 2e and normally tends to push the shaft 4 and gear 4b outwardly and hold slots 4e in engagement 85 with the lugs 2f.

The shaft 4 may be squared at the end and preferably projects beyond the member 1c sufficiently to enable a suitable lever or key to be applied thereto and when so applied the shaft 4 and 90 gear 4b can be pushed inward so as to disengage the slots 4e and lugs 2f and when so disengaged the shaft 4 and gear 4b can be turned so as to raise or lower the sash S'.

Where a window has but two sashes to raise 95 and lower, the devices described would be sufficient to operate same. In some cases, as described in the aforesaid application, four sashes are used and the operating devices are substantially duplicated at the opposite side of the frame 100 F. In this case the rack s² on the sash S² meshes with a gear 1bx on a tubular shaft 1x which is journaled in the brackets 2x and 2z attached to the frame F. Gear 1bx has slots 1ex engaging lugs 2ax on the bracket 2z. The shaft 1x is 105 provided on its outer end with a socket 1cx and is moved outwardly by a spring 3x, the parts described being operated similar to the shaft 1 and members connected therewith above described.

110 The rack s³ on sash S³ meshes with a gear

4bx on the shaft 4x similar to shaft 4, the gear 4bx having slots 4ex engaging lugs 2fx on the bracket member 2gx, the shaft 4x and gear 4bx being pushed outwardly by a spring 3ax interposed between the gear 4bx and part 2ex shown.

The shaft 4x and gear 4bx operate to raise or lower the sash S³ in the manner above described for shaft 4 and gear 4b.

In the construction shown in Fig. 3 three sashes

- 10 S, S' and S^{2x} are shown. In this case the rack s on sash S is engaged by gear 1b on tubular shaft 1 which may be extended outwardly and have its outer end internally hexed as indicated at 1p for engagement of a suitable operating tool, the sleeve being journaled in a bracket 2 attached to the frame F. A spring 3 is interposed between the bracket 2 and a washer or collar 1i fast to the shaft 1 as shown. The aforesaid parts are operated as above described in connection with Fig. 1 to raise and lower sash S.

15 The rack on the sash S' is engaged with the gear 4b on the shaft 4 which extends into the shaft 1 and through a bracket 2j on the frame F. In this instance the shaft 4 is provided with an internal square or hexed socket as indicated at 4h for engagement of a suitable operating tool. The shaft 4 and gear 4b are normally pushed outward by a spring 3a interposed between a collar 4k fixed on the end of the shaft 4 and a member 2k attached to the frame F. The parts are operable to raise or lower the sashes S', Fig. 3, in the manner above described for similar parts in Fig. 1.

20 The third sash S^{2x}, shown in Fig. 3, may be a glazed sash but is shown as a screen sash; the rack s⁴ thereon meshes with a gear 4ez on the shaft 4z similar to shaft 4, the shaft being journaled in brackets 2ez and 2w attached to the frame F at opposite sides of the gear 4ez. The shaft 4z is normally forced outward by a spring 3az interposed between the bracket 2w and the collar 4w on shaft 4z. The outer end of shaft 4z has a socket 4h for engagement with an operative tool.

25 In the construction shown in Fig. 3, instead of a positive clutch engagement between the gears and brackets, friction clutches may be employed. As shown, a friction disk 5 is interposed between bracket 2 and the gear 1b. A friction disk 5a is interposed between bracket 2j and the collar 4k; and a friction disk 5b is interposed between bracket 2w and the gear 4ez. When the gear 1b is moved inwardly it will disengage clutch 5 but will be reengaged therewith as soon as the inward pressure on shaft 4 is released. Similarly when gear 4b is pushed inward the collar 4k will be disengaged from the clutch 5a but will be reengaged therewith when the shaft 4 is moved outward; and when gear 4ez is moved inward it will be disengaged from clutch 5b but will be reengaged therewith as soon as the pressure is released.

30 It is evident from the drawings and description that if a suitable crank or tool is engaged with the outer end of any one of the shafts and pushed inward the gear connected with such shaft will also be moved inward and disengaged from the clutch or device which normally prevents its rotation, and the sash can then be raised or lowered by turning the shaft. As soon as the endwise pressure on the shaft is released the spring will force the shaft and gear outwardly and the

clutch will reengage and lock the gear to the frame and hold the sash in adjusted position.

35 The outer ends of the shafts can be arranged for either an exterior or interior means for non-rotary engagement with the crank and when the crank is engaged and the shaft pushed in then the related sash can be raised or lowered at will.

I claim:

1. Window sash operating devices comprising a plurality of independently endwise movable and rotatable axially aligned and nested shafts, a gear fixed on each shaft adapted to engage a rack on a related sash, spring means for holding each shaft in normal position, and means for locking the gear when its shaft is in normal position, the related locking means being disengaged by endwise movement of the shaft out of normal position and being re-engaged upon the return of said shaft to normal position.

40 2. In window sash operating devices comprising a tubular endwise movable shaft, a gear on said shaft adapted to engage a rack on a sash, a second endwise movable shaft disposed axially of and extending through the tubular shaft, a gear on the second shaft adapted to engage a 100 rack on another sash, and means for locking each gear when its shaft is in normal position, springs for moving the shafts endwise to normal position; said shafts being independently longitudinally movable inward to disengage the related 105 locking means and permit the shaft and gear to be rotated to raise or lower the related sash, the locking means being re-engaged on the return of the shaft to normal position.

45 3. In combination; a tubular endwise movable shaft mounted in fixed bearings, a gear on said shaft adapted to engage a rack on a sash; a second endwise movable shaft extending axially through the tubular shaft, a gear on said second shaft adapted to engage a rack on another sash; 110 independent clutch devices for locking any gear when its related shaft is moved outward, and independent springs for moving the shaft outward; the related clutch being disengaged by the inward longitudinal movement of the related 115 shaft and re-engaged upon the return of said shaft to normal position.

50 4. Sash operating devices for windows having a plurality of movable sashes each provided with a rack; comprising a support, a tubular endwise 120 movable shaft mounted in bearings in said support; a gear on said tubular shaft engaging the rack on one sash; a second endwise movable shaft extending axially of and through the tubular shaft; a gear on said second shaft engaging the 125 rack on the other sash; independent clutch devices for locking each gear to a relatively fixed member on the support when its shaft is moved outward to normal position; and independent springs normally moving the shafts outward to 130 keep the related clutch members engaged; said clutches being respectively disengaged by the inward longitudinal movement of the related shaft; said shafts having their outer ends adapted to be engaged by a manually operable member and 135 being independently longitudinally movable inward to disengage the related locking means and then rotated to raise or lower the related sash; the locking means being re-engaged on the return of the shaft to normal position.

DAVID E. ROSS.
